The ornamental design for a medical vial access device, as shown and described.

DESCRIPTION

FIG. 1 is a perspective view of a medical vial access device showing an embodiment of our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

Portions of the medical vial access device shown in dashed lines in FIGS. 1-8 depict unclaimed portions of the medical vial access device that are included for environmental purposes only.
